US0D1114446S

(12) **United States Design Patent** (10) **Patent No.:** **US D1,114,446 S**
(45) **Date of Patent:** **** Feb. 17, 2026**

(54) **CONTAINER**

(71) Applicant: **YETI Coolers, LLC**, Austin, TX (US)

(72) Inventors: **Dustin R. Bullock**, Austin, TX (US);
Steven M. Scott, Austin, TX (US);
Colby Brunet, Austin, TX (US)

(73) Assignee: **YETI Coolers, LLC**, Austin, TX (US)

(**) Term: **15 Years**

(21) Appl. No.: **29/846,795**

(22) Filed: **Jul. 19, 2022**

(51) LOC (15) Cl. **07-09**

(52) U.S. Cl.

USPC **D7/603; D32/53**

(58) **Field of Classification Search**

USPC **D7/603–608; D24/227, 231, 232;**
